UNITED STATES PATENT OFFICE.

EMIL O. JANECK, OF MADISON, WISCONSIN.

VENTILATOR.

1,080,453.

Specification of Letters Patent.

Patented Dec. 2, 1913.

Application filed July 10, 1912. Serial No. 708,626.

To all whom it may concern:

Be it known that I, EMIL O. JANECK, a citizen of the United States, residing at Madison, in the county of Dane and State of Wisconsin, have invented new and useful Improvements in Ventilators, of which the following is a specification.

This invention is an improved ventilator, especially adapted for use in window openings but also adapted for use in other connections, the object of the invention being to provide an improved ventilator which may be readily placed in or removed from a window, which is adjustable to enable it to fit a window of any ordinary size and which also serves to admit light and air to a room without creating a draft across the room and to exclude rain, wind, and snow.

The invention consists in the construction, combination and arrangement of devices hereinafter described and claimed.

In the accompanying drawing:—Figure 1 is an elevation of a ventilator constructed in accordance with my invention, showing the inner side of the ventilator. Fig. 2 is a vertical sectional view of the same on the plane indicated by the line *a—a* of Fig. 1. Fig. 3 is a horizontal sectional view on the plane indicated by the line *b—b* of Fig. 1.

In accordance with my invention, I provide a suitable frame which is here shown as comprising a pair of vertical end bars 1 and a cross bar 2 arranged at and connecting the lower ends of the end bars. The said end bars are here shown as and are, preferably channelled bars, made of sheet metal and are adapted to be readily fitted in the grooves in the sides of a window frame in which a sash operates. The ventilator frame may be fitted either above or below a sash as may be desired. The bar 2 comprises a pair of elements 3—4 which are slidably related together and are, respectively, connected to the end bars 1, the element 3 being formed at its upper and lower sides with outturned flanges 5 which engage the upper and lower sides of the element 4 so that the said elements are connected together and are yet adapted for sliding relative movement, according to the width of the window or other opening in which the ventilator is used.

My improved ventilator includes a series of slats. These slats are arranged in pairs. The lower slat 6 of each pair slightly overlaps the lower portion of the upper slat 7. The slats are preferably made of sheet metal

and are arcuate in form cross sectionally and arranged with their concaved faces opposed to each other, the concaved face of each lower slat being presented to the outer side 60 of the ventilator and the concave face of each upper slat being presented to the inner side of the ventilator. Each of the slats 7—6 comprises a pair of cross sectional arcuate members 8—9 which are, respectively, attached to the end bars 1 and are slidably related so that the ventilator may be adjusted longitudinally to fit in a window of any ordinary size. Each member 8 is here shown as formed at its upper and lower 70 sides with flanges 10, bent therefrom and which engage the corresponding upper and lower portions of the member 9 so that the said members 8—9 of the slats are connected together and yet adapted for longitudinal 75 adjustment.

It will be observed upon reference to Fig. 2 of the drawing that the cords of the arcs formed by the reversely arranged and opposed members of the pairs of slats are 80 inclined upwardly and inwardly and that owing to the shape and arrangement of the slats, while they serve to freely admit light and air also serve to deflect currents of air upwardly and, hence, prevent drafts from 85 going across the room and direct the same upwardly to the ceiling. Moreover, the slats of my ventilator, owing to their construction and arrangement serve effectually to prevent the entrance of rain and snow. 90

The members 7—8, owing to the fact that their concave surfaces are opposed and also owing to the fact that the cords of their arcs are inclined and that the members 7 are higher than the members 8 cause currents of 95 air which pass into the room through the ventilator to be deflected upwardly and caused to whirl and form vertices between the members 7—8 so that a considerable portion of the strength of said currents is expended in 100 forming the vertices and as the currents escape from between the said members they pass upwardly and close to the inner side of the ventilator. Such currents as they enter above each member 7 and under the 105 next higher member 8 are caught and also carried upwardly by the first-named currents so that the ventilator while admitting air to the room in the window opening in which it is used prevents the currents of air 110 from blowing directly across the room. The lower edge of each upper member 7 on the

outer side of the ventilator extends outwardly therefrom beyond the vertical plane of the lower edge of each lower member and the upper edge of each lower member, on 5 the inner side of the ventilator extends inwardly beyond the vertical plane of the upper edge of its corresponding upper member. This construction and arrangement of the members increases their efficiency in 10 forming vertices in the currents between them.

While I have herein shown a preferred form of my invention, I would have it understood that changes may be made in the 15 form, construction and proportion of the several parts without departing from the spirit of my invention and within the scope of the appended claims.

I claim:—

20 1. A ventilator of the class described including a pair of inclined slats having opposed concaved faces and arranged in partially overlapping relation, one higher than the other, the concaved face of the lower 25 slat being presented to the outer side of the ventilator.

2. A ventilator including a pair of slats of arcuate form cross sectionally, said slats being arranged in partially overlapping relation, one in a higher plane than the other and with their concaved faces opposed. 30

3. A ventilator including a pair of slats of arcuate form cross sectionally, said slats being arranged in partially overlapping relation, one in a higher plane than the other 35 and with their concaved faces opposed, the concaved face of the lower slat being presented to the outer side of the ventilator and that of the upper slat being presented to the inner side of the ventilator. 40

4. A ventilator including a pair of slats of arcuate form cross-sectionally, said slats being arranged in partially overlapped relation, one higher than the other and with their concave faces opposed, the concave 45 face of each lower slat being presented to the outer side of the ventilator and that of the upper slat being presented to the inner side of the ventilator, the lower edge of each upper slat projecting outwardly from the 50 ventilator beyond the vertical plane of the lower edge of its companion lower slat and the inner upper lower edge of each lower slat projecting inwardly from the ventilator beyond the vertical plane of the inner edge of 5 its companion upper slat.

In testimony whereof I affix my signature in presence of two witnesses.

EMIL O. JANECK.
